UNITED STATES PATENT OFFICE.

FRIDRICH SEIPELT, OF NEW YORK, N. Y.

DESIGN FOR A LAMP-STANDARD.

SPECIFICATION forming part of Design No. 17,161, dated March 1, 1887.

Application filed January 11, 1887. Serial No. 224,077. Term of patent 3½ years.

To all whom it may concern:

Be it known that I, FRIDRICH SEIPELT, of the city, county, and State of New York, have invented a new and original Design for Lamp-
5 Standards, of which the following is a specification.

The nature of my design is fully illustrated in the accompanying drawings, of which—

Figure 1 is a front view of my newly de-
10 signed lamp standard, and Fig. 2 is a rear view
of the same.

Similar letters of reference indicate corresponding parts.

The main feature of my design consists in a
15 lamp-standard having the shape of a bee-hive,
and leaves and bees on the surface of the same.

The body of the lamp standard A is made in
the conventional shape of a bee-hive. B rep-
resents the opening or entrance; C, twigs and
20 leaves on the outside of the hive. D D rep-
resent bees on the hive and twigs and around

the entrance or opening B. E is the base of
the hive, and F ball-shaped legs.

Having thus described my design, I claim as
new and desire to secure by Letters Patent— 25

1. The design for a lamp-standard, substan-
tially as herein shown and described, the same
consisting of the conventional representation
of a bee-hive, twigs, and branches, and bees
on the twigs and branches and on the hive. 30

2. The design for a lamp-standard, substan-
tially as herein shown and described, the same
consisting of the conventional representation
of a bee-hive, twigs, branches, and bees, the
base E, and the ball-shaped legs F. 35

In testimony that I claim the foregoing as
my invention I have signed my name in pres-
ence of two subscribing witnesses.

FRIDRICH SEIPELT.
